UNITED STATES PATENT OFFICE.

GUSTAF A. WALLIN, OF SCOTCH PLAINS, NEW JERSEY, ASSIGNOR TO A. KIMBALL COMPANY, OF NEW YORK, N. Y., A CORPORATION OF NEW YORK.

UNIT PACKAGE.

1,391,433.

Specification of Letters Patent. Patented Sept. 20, 1921.

Application filed January 6, 1919. Serial No. 269,739.

To all whom it may concern:

Be it known that I, GUSTAF A. WALLIN, a citizen of the United States, residing at Scotch Plains, county of Union, State of New Jersey, have invented an Improvement 5 in Unit Packages, of which the following description, in connection with the accompanying drawing, is a specification, like characters on the drawing representing like parts.

This invention relates to improvements in unit packages of superposed articles which it is desirable to secure together without inclosing them in a wrapper or carton, such 15 as a package of sealing rings for jars.

One of the objects of the present invention is to provide a unit package of superposed articles, such as rings, in which the means transversely encircling and retaining 20 said articles in assembled position shall be capable of receiving and displaying such identifying indicia and other information as may be desirable.

Another object of the invention is to provide 25 a unit package comprising a series of superposed articles having binding strips capable of a permanent set when bent and provided with a sufficiently broad surface to prevent injury to the articles to which they 30 are applied.

A further object of the invention is to provide 35 a unit package of hollow articles in which the ends of the binding strips are interlocked or otherwise secured together preferably within the hollow central portion of the package.

Other objects of the invention and the nature thereof will more fully appear from the following description and the accompanying 40 drawing and will be particularly pointed out in the claim.

A preferred embodiment of the invention is illustrated in the accompanying drawing in which—

45 Figure 1 is a perspective view of a unit package of superposed flat rings, embodying my invention;

Fig. 2 is a vertical sectional view showing the binding strip embracing said rings and 50 having its ends interengaged to lock them together;

Fig. 3 is an enlarged transverse sectional view of the binder.

55 The principal object of the present invention is to provide a unit package of super-

posed articles having a binding member presenting a surface of sufficient area to receive and display desired indicia such as trade names, trademarks and attractive advertising slogans which will catch the eye of a prospective purchaser and thereby serve to promote the sale of the package. The binding member may also bear identifying indicia such as price marks, size marks and other information which will aid the merchant in the identification and selection of the articles.

A further object of the invention is to provide a unit package having one or more binding members provided with sufficient area to receive and display indicia, said binding members being formed of a pliable material capable when bent of retaining a permanent set, the ends of said binding members preferably being provided with interengaging portions which will lock the binding member firmly in its engagement with the articles.

An important feature of the invention resides in providing a binding member of the character above specified with interengaging ends of a character which may be easily released when the articles are to be used.

A preferred form of unit package of the character above described which is illustrated herein comprises a number, preferably a dozen, superimposed rings 1 for sealing jars which may be held together by one or preferably by a plurality of binder strips 2 disposed at circumferential points in the superimposed position of said rings.

The binders 2 are of sufficient width to receive and display desired indicia and preferably are formed of or comprise a material capable of retaining a permanent set when bent. The preferred form of binder which is illustrated herein comprises two plies of paper 3 pasted or cemented together and inclosing between them a wire or bar 4 of pliable substantially non-resilient material so that when the binder is bent around the superimposed articles it will lie closely adjacent the edges or walls of said articles without any tendency to spring away. The construction of this binder may be similar to that disclosed in my prior Patent No. 1,073,828, granted Sept. 28, 1913, for pinless marking ticket, the non-resilient stiffening member being made of such character as to perform the function required.

The binder when applied to the superimposed rings as illustrated in Figs. 1 and 2 comprises a base portion 5 which engages the flat surface of the lowermost ring, a side portion 6 which extends alongside and contacts with the outer cylindrical surface of the superimposed rings, a transverse upper portion 7 which engages the flat upper surface of the top ring and an inner side portion formed of the two end portions 8 and 9 of the binder which when locked forms a substantially continuous support for the inner walls of the superimposed rings. The end portion 8 of the binder is bent back 15 upon itself to form a hook 10 while the opposite end portion 9 is bent substantially at right angles in such a manner as to provide a projection 11 which will enter the re-entrant portion of the hook 10. The inter- 20 engaging ends are then pressed down to form the locking joint illustrated in Fig. 2.

By reason of the broad area of contact between the binder and the rings a firm grip is secured upon the rings which will hold 25 them from lateral displacement even if a single binder is used. Preferably however, the rings are held together at a plurality of

circumferential points in the superimposed position of the rings by binders of the character specified bent snugly around transversely of the rings. Two of such binders are illustrated in Fig. 1 as applied to diametrically opposite portions of the superimposed rings.

Having fully described my invention, what I claim as new and desire to secure by Letters Patent is:

A unit package comprising a plurality of superimposed flat rings secured together by a plurality of flat binding strips bent transversely there-around, comprising plies of paper presenting a surface to receive identifying indicia and having a flexible non-resilient member there-between, capable of a permanent set and of sufficient rigidity to retain said rings firmly in superimposed position and having hooked interengaging end portions lying closely adjacent the inner walls of said superimposed rings whereby lateral displacement thereof is prevented.

In testimony whereof, I have signed my name to this specification.

GUSTAF A. WALLIN.
